United States Patent Office

Des. 193,585

Patented Sept. 11, 1962

193,585

CONTAINER FOR DAIRY PRODUCTS OR THE LIKE

Clara Virginia Eicholtz, Midland, Mich., assignor to The Dow Chemical Company, Midland, Mich., a corporation of Delaware

Filed Dec. 29, 1960, Ser. No. 63,386

Term of patent 14 years

(Cl. D58—17)

Fig. 2

Fig. 1

FIGURE 1 is an elevational view of a container for dairy products or the like showing my new design; FIGURE 2 is a top plan view thereof; FIGURE 3 is a perspective view thereof; and FIGURE 4 is a fragmentary vertical sectional view thereof, taken on line 4—4 of FIGURE 1.

I claim:

The ornamental design for a container for dairy products or the like, as shown.
